REMOVAL OF VANADIUM AND/OR SODIUM FROM PETROLEUM AND PETROLEUM PRODUCTS WITH ALUMINA AND IRON OXIDE

Frederick William Bertram Porter and Roy Purdy Northcott, Sunbury-on-Thames, England, assignors to The British Petroleum Company Limited, a British joint-stock corporation

No Drawing. Application June 16, 1953,
Serial No. 362,144

Claims priority, application Great Britain June 18, 1952

1 Claim. (Cl. 196—24)

This invention relates to the removal of vanadium and/or sodium from petroleum and petroleum products.

In co-pending U. S. application Serial No. 263,956, filed December 28, 1951, there is described a process in which vanadium and/or sodium are/is removed from petroleum or petroleum products by contact with bauxite in the presence or absence of hydrogen and under conditions of temperature and pressure such that the vanadium and/or sodium are/is deposited on or incorporated with the bauxite. It was later discovered that the degree of vanadium and/or sodium removal under any given set of operating conditions tended to vary with bauxites of different origins.

It has now been found that vanadium and/or sodium in petroleum or petroleum products can be removed by treatment with iron oxide on alumina.

According to the invention therefore, a process for removing vanadium and/or sodium from crude petroleum or a petroleum product comprises contacting the crude petroleum or petroleum product with a contact material consisting essentially of iron oxide and alumina, in the presence of hydrogen and under conditions of temperature and pressure such that vanadium and/or sodium are/is deposited on the contact material.

The contact material preferably contains from 5—15% by weight of ferric oxide the remainder consisting essentially of alumina.

The preferred ranges of operating conditions for the process are as follows:

Space velocity..... 0.5 to 2.0 v./v./hr.
Temperature..... 750° to 800° F.
Pressure..... 500 to 1500 p. s. i. g. a.
Hydrogen recycle rate..... 1000 to 10,000 S. C. F./B.

The process of the invention is particularly adaptable as a pre-treatment process for crude petroleum or petroleum products which are to be passed to a catalytic hydrogenation process for the removal of organically combined sulphur. For example, it has been found that in the hydrofining of crude petroleum and petroleum residues using a catalyst consisting of cobalt and molybdenum

2

oxides supported on alumina, substantial proportions of vanadium and sodium are removed by and deposited on the catalyst and this deposition causes a steady decline in catalyst activity with hours on stream which is not wholly recovered on regeneration in the conventional manner. This invention, therefore, also includes a continuous process wherein a petroleum feedstock containing vanadium and/or sodium is first treated with iron oxide on alumina, as above described, and is then passed to a hydrogenation zone for the removal of organically combined sulphur.

An example of the application of the invention to the treatment of a petroleum residue will now be given.

EXAMPLE

Sodium and vanadium removal from Kuwait 53% volume residue.

Conditions employed

Feedstock.....	Kuwait 53% vol. residue.
Space velocity.....	1.0 v./v./hr.
Temperature.....	780° F.
Pressure.....	1000 p. s. i. g. a.
Hydrogen recycle rate.....	4000 S. C. F./B.
Direction of flow.....	Upward.
Duration of test.....	50 hours.

Results obtained

IRON OXIDE ON ALUMINA
[12.8% wt. Fe₂O₃]

	Feedstock	Product (bulk over 50 hrs.)
Vanadium, p. m.....	41	21
Sodium, p. m.....	39	28
Sulphur, percent wt.....	3.89	3.42
Specific Gravity, 60° F./60° F.....	0.958	0.943

We claim:

40 A process for removing vanadium and sodium from a crude petroleum feedstock comprising contacting the petroleum feedstock with a contact material consisting essentially of alumina to which has been added 5—15% by weight of ferric oxide in the presence of hydrogen and
45 at a temperature within the range of about 750—800° F. and a pressure within the range of about 500—1500 p. s. i. g. a. such that vanadium and sodium are deposited on the contact material.
